INVENTOR
Amos K. Ersland;
BY *Munn* *Jo* ATTORNEY

UNITED STATES PATENT OFFICE.

AMOS K. ERSLAND, OF MANHATTAN, CALIFORNIA.

WRENCH.

Application filed May 25, 1927. Serial No. 194,099.

My invention relates to wrenches, and its primary purpose is the provision of a wrench having the dual properties of a pipe wrench and a nut wrench and quick adjusting means 5 for the jaws thereof in either use.

It is also the purpose of my invention to provide a wrench in which the handle and jaws thereof act as a compound lever to cause the jaws to positively grip any object 10 placed therebetween and in proportion to the pressure brought upon the handle, my invention being simple in construction with the minimum of working parts, compact in form, strong and durable and quick to adjust. 15

I will describe only one form of wrench embodying my invention, and will then point out the novel features thereof in claims.

In the accompanying drawings, 20 Fig. 1 is a view showing in side elevation one form of wrench embodying my invention.

Fig. 2 is an enlarged view showing the wrench in front edge elevation.

25 Fig. 3 is a view showing the wrench in longitudinal section with the jaws thereof in pipe or nut gripping position.

Fig. 4 is a fragmentary sectional view 30 similar to Fig. 3, and showing the inner jaw in released position to permit adjustment of the outer jaw.

Fig. 5 is a fragmentary sectional view 35 similar to Fig. 3, showing the jaws in non-gripping position with respect to a pipe.

Referring specifically to the drawings, my invention in its present embodiment comprises a handle, the main body of which is preferably constructed from a single sheet of suitable metal or other material shaped 40 and bent to provide an elongated handle portion 15 of U form in cross section, and a pair of ears 16 spaced in parallelism and connected at their forward edges by an elongated block 17 of metal secured in 45 proper position by rivets 18. The handle portion 15 is interiorly provided with a filler 19 formed of wood or other suitable material with its inner end in abutting relation to a metallic block 20, which functions as a 50 spacer, and is secured in place by rivets 21. It is important to note that the handle is open at the front ends thereof between the blocks 17 and 20, and at the top between the block 17 and the upper edge of the intermediate part of the handle portion, such 55 parts being extended beyond the handle por-

tion to serve in connecting the ears 16, but such part terminating short of the upper edges of the ears.

The wrench includes inner and outer jaws 60 designated generally at J and J' respectively, the inner jaw comprising a jaw head 22 having a toothed working surface, and formed on the upper end of a tapered shank 23 pivoted on a pin 24 secured in the ears 65 16 so that the shank is capable of pivotal movements between the ears and in the plane thereof. The lower or inner end of the shank 23 is formed with a toothed projection 25 which constitutes a pawl adapted for engagement with a rack 26 formed on the forward end of an elongated shank 27 of the jaw J'. The jaw J' includes a jaw head 28, the working surface of which is toothed. The shank 27 is slidable, longitudinally between the ears 16, and it is also capable of being swung in the plane of the handle through the provision of the openings in the handle as previously described. In this swinging movement of the shank it rides on 70 a rounded bead 29 on the upper end of the intermediate part of the handle.

The jaw J is yieldably urged in a counter-clockwise direction about the pivot 24 to position the shanks of both jaws so that the 85 heads 22 and 28 will normally occupy parallel positions. This is effected through the medium of a spring 30 riveted at its upper end to the block 17, while its lower end is free and engages the lower end of the shank 90 23. By urging the shank in this manner the pawl 25 is biased into engagement with the rack 26 so as to normally lock the shank 27, and consequently the jaw head 28 in a fixed 95 position of adjustment. To release the shank 27, so that the jaw J' can be adjusted in 100 respect to its parallel position to the jaw J, the jaw J is moved manually to the position shown in Fig. 4 in which the pawl 25 is moved free of the rack 26. As soon as the jaw J is released, however, the spring 30 105 functions to return the pawl 25 to locking position with respect to the rack 26, thereby securing the jaw J' in its new position.

In the operation of the wrench when applied to nuts or other angularly shaped objects, the quick adjustment of the jaw J' can be effected in the manner previously described to fit the wrench to the nut, and following such adjustment the jaws will be 110 maintained in parallel spaced relation during the rotation of the nut in a clockwise

direction through operation of the handle. When pressure is exerted on the handle it is transmitted to the shank 27, and subsequently to the jaw J' through the intermediate part or back of the handle portion, the jaw J also remaining stationary.

In the application of the wrench to pipes and other circular objects, the jaws tend to assume parallel positions when turning the 10 pipe through actuation of the handle, but on reversing the movement of the wrench a relative movement occurs between the handle and the jaw J', so that the latter assumes the position shown in Fig. 5, in which the jaw head 28 is in divergent relation to the jaw head 22, thus releasing the pipe to permit 15 repositioning of the wrench for further turning of the pipe. As clockwise pressure is exerted on the handle the jaw J' tends to 20 return to parallel position with respect to the jaw J, thereby again gripping the pipe to effect turning of the latter. From this operation it will be seen that the wrench functions in the true manner of a pipe wrench, yet is capable of being quickly 25 adjusted, and also used as a nut wrench.

Although I have herein shown and described only one form of wrench embodying my invention, it is to be understood that 30 various changes and modifications may be made herein without departing from the spirit of the invention and the spirit and scope of the appended claims.

I claim as my invention:

35 1. A wrench comprising a handle, an inner jaw having a shank pivoted in the handle to swing in the plane of the handle, an outer jaw having a shank movable longitudinally in the handle, coacting teeth on 40 the jaw shanks for securing the outer jaw in any position of adjustment longitudinally on the handle, and a spring for urging the shank of the inner jaw toward the shank of the outer jaw to releasably maintain the

teeth in engagement with each other, the 45 shank of the outer jaw adapted to fulcrum on a part of the handle at one side of the inner jaw shank pivot so placed that the ratio between the jaw arm and the locking arm of the inner jaw is greater than the 50 ratio between the arms formed between the two points of contact of the inner jaw with the outer jaw and the fulcrum point of the outer jaw shank so as to permit the outer 55 jaw shank to be rocked by the inner jaw and yet the inner jaw shank to be moved to a position in which its teeth are out of engagement with the teeth of the outer jaw shank and thus allow longitudinal adjustment of the outer jaw.

2. A wrench comprising a handle, an inner jaw having a shank pivoted in the handle to swing in the plane of the handle, an outer jaw having a shank movable longitudinally in the handle, coacting teeth on 60 the jaw shanks for securing the outer jaw in any position of adjustment longitudinally on the handle, a spring for urging the shank of the inner jaw toward the shank of the outer jaw to releasably maintain the teeth in 70 engagement with each other, there being a shoulder on the handle positioned to provide a fulcrum point about which the outer jaw shank is adapted to pivot so placed that the ratio between the jaw arm and the locking arm of the inner jaw is greater than the ratio between the arms formed between the two points of contact of the inner jaw with the outer jaw and the fulcrum point of the outer 75 jaw shank to allow the outer jaw in 80 contact with the inner jaw end to occupy a divergent position with respect to the inner jaw and to permit the inner jaw shank to be moved to a position in which its teeth are out of engagement with the teeth of the outer 85 jaw shank, whereby longitudinal adjustment of the outer jaw is permitted.

AMOS K. ERSLAND.
